UNITED STATES PATENT OFFICE

PAUL HERTZSCH, OF MARKRANSTADT NEAR LEIPZIG, GERMANY

DRYING AND CLEANING HIDES

Application filed August 1, 1929, Serial No. 382,729, and in Germany August 14, 1928.

My invention refers to means whereby hides can be dried and cleaned in a more perfect manner than was hitherto possible.

Hitherto hides, in order to be dried, were suspended in wet condition from rods disposed in large drying chambers and were exposed to the action of hot air. However, this way of drying the hides consumes much time and requires large chambers. Furthermore in consequence of an uneven distribution of the hot air the hides are not uniformly brought in contact with the air, those disposed near the air inlet being dried more quickly than those near the outlet. For the air on passing through the drying chamber transmits its heat to the first hides which it encounters, while taking up the moisture and being cooled correspondingly.

The cleaning of the hides has hitherto been carried through separately from the drying, however more especially if dyed hides are treated, much time is consumed in the cleaning process.

According to the present invention these drawbacks are avoided, the hides to be dried and, if desired, to be also cleaned being arranged in a tightly closed rotary drum in which they are exposed to hot air which is constantly removed from the drum by suction together with the vapors of moisture developed by evaporation, so that the container is partly evacuated, whereby the drying process is greatly shortened.

In the same manner the hides may be either dried or cleaned separately, or both the drying and cleaning can be carried out in one operation.

Preferably the quantity of fresh air introduced into the drum can be adjusted by suitable throttling means, such as a valve, cock, or the like and the air supply pipe is preferably heated by the source of heat which also heats the drum itself.

It is important that by the means mentioned above the quantity of air introduced into and sucked from the drum can be regulated in such manner that a predetermined vacuum can be permanently maintained within the drum. A gauge or manometer can be

provided on the drum for the control of the vacuum.

If the drying shall be accompanied by a cleaning of the hides, cleaning means, such as fine sand, chips of wood or the like may be introduced into the drum together with the hides.

Hides fixed on boards under tension may be dried also in the drum.

In the drawing affixed to the specification and forming part thereof a drying and cleaning device embodying my invention is illustrated diagrammatically by way of example.

In the drawing
Fig. 1 is an axial section, while
Fig. 2 is a cross-section.

Referring to the drawing, *a* is a drum, *b* is the metal wall and *c*, *d* are the wooden end walls or covers. *e*, *f* are journals fixed in the covers *c*, *d* and *g*, *h* are bearings supporting them. The journals *e*, *f* are hollow and connected by means of stuffing boxes *t*, *t'* with the air supply pipe *k* and suction pipe *i*, respectively. *l* is a pulley or the like mounted on the journal *e*, *m* is a pan or other heating means arranged below the drum and the lower part *n* of the air supply pipe. *r* is a regulating valve inserted in this pipe and *s* is a manometer mounted on the pipe *k*. *q* are perforated plates covering the openings of the hollow journals *e*, *f*.

p are wooden boards or ledges fixed to the inner cylindrical wall of the drum and projecting radially into it and *o* is a manhole.

On the hides having been introduced into the drum through the manhole *o*, the drum is set rotating and air is introduced through pipes *n*, *k* and journals *e*, while suction is produced in pipe *i* by means of a suitable pump (not shown). The air entering through *n*, *k* is heated in its passage over the pan *m* and the air in the drum *a* is heated also. The valve *r* allows regulating the quantity of air entering the drum and the manometer *s* allows watching the vacuum in the drum.

The hides in the drum are carried along by the ledges *p* and on reaching the top of the drum will drop down to be carried along anew by another ledge. In this manner the

100

hides are exposed on all sides to contact with the hot air and the moisture is evacuated therefrom by the partial vacuum maintained in the drum, in consequence of the difference 5 between the air pressure at *e* and *f*.

If cleaning agents have been introduced into the drum together with the hides, the drying of the hides will be accompanied by a cleaning action.

10 Various changes may be made in the details disclosed in the foregoing specification without departing from the invention or sacrificing the advantages thereof.

I claim:—

15 1. The method of drying and cleaning hides comprising moving such hides in the presence of a mechanical cleaner, and subjecting said hides and said cleaner to a flow of heated air at a pressure below atmospheric 20 while retaining said mechanical cleaner against entraining by said flow.

25 2. The method of drying and cleaning hides comprising moving such hides in the presence of a mechanical cleaner, and subjecting said hides and said cleaner to a flow of heated air at a constant pressure below atmospheric while retaining said mechanical cleaner against entraining by said flow.

30 In testimony whereof I affix my signature.
PAUL HERTZSCH.
